UNITED STATES PATENT OFFICE.

ERNEST T. BECK, OF MERIDEN, CONNECTICUT, ASSIGNOR TO INTERNATIONAL SILVER COMPANY, OF MERIDEN, CONNECTICUT, A CORPORATION OF NEW JERSEY.

DESIGN FOR A CANDELABRUM.

Application filed January 29, 1925. Serial No. 12,197. Term of patent 14 years.

To all whom it may concern:

Be it known that I, ERNEST T. BECK, a citizen of Germany, residing at Meriden, in the county of New Haven and State of Connecticut, have invented a new, original, and ornamental Design for Candelabra, of which the following is a specification, reference being had to the accompanying drawing, forming part thereof.

The figure is a perspective view of a candelabrum showing my new design.

I claim:

The ornamental design for a candelabrum as shown.

ERNEST T. BECK.

Witnesses:

WALTER A. MORRIS,
ROBERT R. KINTZ.
